UNITED STATES PATENT OFFICE

2,218,717

BANDING DEVICE

Glenn L. McKee, Bakersfield, Calif., assignor to
McKee Brothers Corporation, Bakersfield, Calif.

Application September 25, 1939, Serial No. 296,376

5 Claims. (Cl. 24—20)

My invention relates to banding devices. The principal object of the invention is to provide a banding device made from a single thickness of metal.

Another object of the invention is to provide a banding device that has an integral head for locking an end of the band, but without a shoulder between the head and the band.

The invention also comprises novel details of construction and novel combinations and arrangements of parts, which will more fully appear in the course of the following description.

In the drawings, like reference characters designate similar parts in the several views.

Figure 1 is a broken, plan view of an embodiment of the invention in a locked position.

Figure 2 is a section taken on the line 2—2 of Figure 1.

Figure 3 is a broken, plan view of another form of the invention, in a locked position.

Figure 4 is a section taken on the line 4—4 of Figure 3.

Figure 5 is a broken, plan view of still another form of the invention.

Figures 6 and 7 are respectively successive steps in locking the band shown in Figure 5.

Figure 7 is a section taken on the line 7—7 of Figure 5.

Figure 8 is a plan view, partly broken away, illustrating another modification.

Figure 9 is an enlarged, transverse section taken on the line 9—9 of Figure 8.

Figure 10 is an enlarged, broken, plan view of the modification shown in Figure 8 but in a locked position.

Figure 11 is a section taken on the line 11—11 of Figure 10.

Referring more in detail to the drawings, in the form shown in Figure 1, a band 12 has an integral, enlarged head 13. The head 13 is elongated, as shown at 14, to underlie the portion of the band 12 adjacent the locking tip. The locking tip of the band 12 is shown at 15.

The head 13 is slotted, as shown at 16 and 17, and the portion of the head 13 between the slots is pushed out of the plane of the remainder of the head 13, as shown at 18.

In locking this form of the invention, the tip 15 of the band 12 is layed upon the end 14 and inserted through the slots 17 and 16. The tip 15 is then bent back upon itself and upon the pressed out member 18. The outermost portion of the tip 15 may be crimped, as shown at 19, to further lock the band in position.

In the form shown in Figure 3 a band 20 has a

head 21. The head 21 is slotted as shown at 22, 23, 24 and 25. The metal of the head 21 is bent upwardly between the slots 22 and 23 and between slots 24 and 25, to provide upwardly bent portions 28 and 29 respectively, considering Figure 3 as being a top view. The portion of the head 21 between the slots 23 and 24 is left in the same plane as the head 21. In this form a tongue 27 on the head 21 is bent backward under the head.

In locking this form, the tip 26 of the band 20 is inserted under the upwardly bent portions 29 and 28 and the tip 26 is then bent back upon the band 20 and upon the top of the bent up portions 28 and 29. The broken lines 30 illustrate the method of inserting the tip 26 under the bent up portions. The entire lock may then be placed under pressure, in order to crimp the band 20 at the slots 22, 23, 24 and 25. The crimping of the band 20 is best shown in Figure 4.

In the form shown in Figure 5, a band 31 has an integral head 32 provided with a tongue 33. The head 32 is slotted as shown at 34 and 35.

In practice the head 32 is bent, as shown at 36, and tip 37 of the band 31 is thereupon inserted through the slot 34 at the bend 36. The tip 37 of the band is thereupon fed down through the slot 35 and folded around an upwardly bent portion 38 of the head. The tip 37 is then bent down upon itself and upon the upwardly bent portion 30 38. Thus far is shown in Figure 6. Thereafter as the head 32 is bent down upon the bent tip 37, as shown in Figure 7, which is the locked position.

In the form shown in Figure 8, a band or strap 40 has a tip 41 at one end and an enlarged, integral head 42 at the other end. A tongue is punched from the head 42, leaving an opening 44 therein. The tongue is mounted on a jaw 45, which is formed by raising the jaw from the plane of the head 42, the raised portions being 40 shown at 46. An edge of the jaw 45 has been severed from the body 42, as shown at 47, prior to the raising of the jaw 45. The slit 47 has curved ends 48, which minimize strain and tearing at these points.

In practice, the tip 41 is inserted between the tongue 43, the jaw 45 and the head 42. The tip 41 is then bent back upon the jaw 45 and the tongue 43 is bent over the tip 41, as shown in Figure 11. The edge of the tongue 43 may be curved around the bend of the tip 41, as shown at 49.

In the use of the present invention, in each of the forms the band or strap is passed around the article or group of articles to be banded and the tip of the band or strap is locked in position upon

the integral head by one of the means heretofore described. The locking details of the several forms have been described immediately following their respective descriptions.

5 While I have illustrated and described what I now regard as the preferred embodiment of my invention, the construction is, of course, subject to modifications without departing from the spirit and scope of my invention. I, therefore, do not wish to restrict myself to the particular form 10 of construction illustrated and described, but desire to avail myself of all modifications which may fall within the scope of the appended claims.

Having thus described my invention, what I 15 claim and desire to secure by Letters Patent is:

1. A banding device comprising a strap, a head 20 on the strap, a jaw extending outwardly from the head and disposed in a plane substantially parallel thereto, the jaw being arranged on the head to provide a passage between the jaw and the head, the passage extending longitudinally of the head and strap and being open at both ends, and a bendable tongue on the jaw extending therefrom in a direction opposite to the direction 25 that the strap extends from the head when the device is flat and prior to bending of the tongue, the head, jaw and tongue being of a single sheet of material, the tongue also being spaced from the head at a side thereof and disposed in a plane substantially parallel with the head, the strap in a banding position being inserted through both ends of the passage and disposed beneath the tongue.

2. A banding device comprising a strap, a head 30 on the strap, a jaw offset from the head but disposed in a plane substantially parallel thereto,

the jaw being arranged on the head to provide a passage between the jaw and the head, the passage extending longitudinally of the head and strap and being open at both ends, and a bendable tongue on the jaw also offset from the head 5 and extending in a direction lengthwise of the head and strap.

3. A banding device comprising a strap, a head on the strap, the head and strap having a continuously smooth inner side for engaging an article or articles being banded, a jaw extending outwardly from the head and arranged to provide a passage between the jaw and the head, the passage being open at both ends, considering its length as being substantially parallel with the 15 length of the head and strap, and a bendable tongue connected with the jaw and extending in a direction lengthwise of the head and strap.

4. A banding device comprising a strap, a head on the strap, the head having an opening in the 20 face thereof, a jaw extending outwardly from the head and connected with the head at the sides of the opening, the jaw being arranged to provide an open-ended passage between the jaw and the head, and a bendable tongue on the jaw 25 disposed opposite a portion of the opening in the head and bendable to a position extending lengthwise of the head and strap.

5. A banding device comprising a strap, a head on the strap, a jaw extending outwardly from the 30 head and arranged to provide an open-ended passage for the strap, and a tongue connected with the jaw and bendable to a position extending lengthwise of the head and strap, the strap, head, jaw and tongue being of a single sheet of material. 35
